UNITED STATES PATENT OFFICE.

MARIUS A. BAUER, OF WORCESTER, MASSACHUSETTS, ASSIGNOR TO M. J. WHITTALL ASSOCIATES, A VOLUNTARY ASSOCIATION OF MASSACHUSETTS.

ACTUATING MECHANISM IN ORIENTAL-RUG LOOMS.

Application filed May 18, 1927. Serial No. 192,444.

This invention relates to improvements in an oriental rug loom of the general type shown in the prior patents to Renard No. 894,287, No. 1,164,117 and No. 1,437,682. The 5 loom shown in these Renard patents is designed to weave rugs or carpets with the tuft yarn looped or knotted into the fabric in exact duplication of an oriental hand-weaver's knot. These looms necessarily involve many complicated mechanical movements for the accomplishment of this result, and it is the general object of my present 10 invention to simplify the actuating mechanism and connections for certain parts of such a loom.

More specifically, it is an object of my invention to simplify the mechanism and connections by which the yarn grippers or pliers are opened and closed and are moved longitudinally and by which the yarn dividers are given their several operative movements.

My invention further relates to arrangements and combinations of parts which will be hereinafter set forth and more particularly pointed out in the appended claims.

A preferred form of the invention is shown in the drawings in which

Fig. 1 is a front elevation of certain parts of an oriental rug loom;

Fig. 2 is a plan view, partly in section, of the parts shown in Fig. 1;

Fig. 3 is a rear elevation of certain of said parts; and

Fig. 4 is a partial side elevation of a pair of yarn grippers or pliers.

Plier mechanism.

I will first describe the mechanism for actuating the yarn grippers or pliers. One of these pliers is best shown in Figs. 2 and 4, and comprises a pair of sliding members 10 and 11 connected to studs 12 and 13 (Fig. 2) in a rock plate 14 having a rearward extension 15. The sliding member 10 is provided 45 with a diamond-shaped opening 16 through which the tuft yarn Y may project and the member 11 is provided with a forked end 17 adapted to grip the yarn against the outer end portion of the member 10. For a more 50 complete description of the construction and operation of the grippers or pliers, reference is made to the Renard Patent No. 1,437,682 above noted.

A rod 20 is slidable adjacent the rearward projections 15 and is provided with

studs 21 adapted to engage said projections and to rock the plates 14 in one direction. A spring 22 is connected between a pin 23 on the rock plate 14 and a pin 24 on the sliding bar 20, and acts to yieldingly move 60 the rock plate in the other direction. It will be understood that the bar 20 extends the full width of the loom and that a considerable number of rock plates 14 are actuated simultaneously by the bar 20.

For reciprocating the bar 20, I provide a face cam 25 (Fig. 3) mounted on a shaft 26 which is connected by bevel gears 27 and 28 with a drive shaft 29 intermittently rotated in timed relation with other parts of 70 the loom. The cam 25 is provided with inner and outer concentric portions 30 and 31 connected by inclined cam portions 32 and 33. A bell crank 35 is mounted on a fixed pivot 36 and is provided with a cam roll positioned 75 in the track of the cam 25. The arm 37 of the bell crank is connected by a link 38 to a small bell crank 39 pivoted at 40 and connected by a link 41 to a head 42 secured to the end of the sliding bar 20.

As the cam 25 is rotated, the bar 20 is given operative movements in opposite directions, with intervening dwells of substantial duration. The length of the stroke may be varied by connecting the link 38 to different 85 holes 43 in the bell crank arm 37.

By the actuating mechanism and connections above described, the sliding bar 20 is given reciprocating movements of any desired extent and the mechanism operates 90 more effectively than has been previously the case.

Divider mechanism.

Another important part of my invention 95 relates to the provision of improved mechanism and connections for actuating the dividers 50 (Fig. 2) by which the pairs of warp threads are raised and manipulated during the insertion of the pile yarn and the formation of a knot.

These dividers 50 are mounted in transverse bearings in a divider shaft 51 and are each provided with pinions 52 engaged by a sliding rack 53. As the rack is moved 105 lengthwise, the dividers are turned on their axes and as the shaft 51 is oscillated the dividers are raised and lowered by swinging about the axis of the shaft 51.

The rack bar 53 is connected to a head 54 110

having a stud 55 extending through an end 56 on a link 57, and also extending through a slotted support 58. The link 57 is adjustably secured by a swivel connection to a pivot 5 of stud 59 rotatably mounted in the lower end of a lever 60 (Fig. 1). The lever 60 is mounted on a fixed pivot 61 and has a cam roll at its upper end engaging a cam groove 62 in the forward face of the bevel gear 27 previously described.

As the gear 27 is rotated, the cam groove causes the lever 60 to oscillate, thus producing reciprocating movements of the rack 53 at the desired times. An arm 65 (Fig. 15) 2) is clamped to the divider shaft 51 and is provided with a stud 66 for a collar 67 to which a link 68 (Fig. 1) is pivoted at 69.

The link 68 is vertically reciprocated by cam mechanism (not shown) which causes 20 the shaft 51 to be oscillated, raising and lowering the dividers 50 as desired. I have thus provided mechanism for oscillating the shaft 51 and reciprocating the rack 53 which is greatly simplified over that previously 25 used and which is effective and reliable for the purposes described.

A carriage 70 (Fig. 2) is provided for moving the yarn grippers or pliers lengthwise of the machine to draw the yarn out 30 of the yarn tubes and the pivot 40 of the bell crank 39 is fixed on the carriage 70. The carriage 70 is provided with studs 71, to which actuating levers 72 are pivotally connected. The levers 72 are mounted to 35 swing about a shaft 73 (Fig. 1) positioned substantially above the carriage 70, and the levers are actuated by links 74 connected to suitable cam mechanism (not shown). The relatively long vertical link 38 (Fig. 3) permits movement of the pivot stud 40 with the carriage 70, without causing substantial angular movement of the bell crank 39.

I have thus provided for all of the essential movements of the pliers and dividers, 45 and have greatly simplified the operative connections therefor.

Having thus described my invention and the advantages thereof, I do not wish to be limited to the details herein disclosed otherwise than as set forth in the claims, but what I claim is:

1. In a loom for weaving oriental rugs, plier-actuating mechanism comprising a longitudinally movable rod for opening and closing a series of yarn pliers, a bell crank, a link directly connecting said bell crank to the adjacent end of said rod, a second bell crank having a cam roll thereon, a cam effective to intermittently actuate said cam roll and bell crank, and a second link directly connecting said two bell cranks.

2. In a loom for weaving oriental rugs, plier-actuating mechanism comprising a longitudinally movable rod for opening and closing a series of yarn pliers, a bell crank,

a link directly connecting said bell crank to the adjacent end of said rod, a carriage on which said pliers and bell crank are mounted, a second cam-actuated bell crank mounted on a fixed pivot at a substantial distance above said carriage, a relatively long vertical link connecting said two bell cranks, and means to reciprocate said carriage, said long vertical link permitting such carriage reciprocation without substantial angular movement of said first bell crank.

3. In a loom for weaving oriental rugs, plier-actuating mechanism comprising a longitudinally movable rod for opening and closing a series of yarn pliers, a bell crank, a link directly connecting said bell crank to the adjacent end of said rod, a second bell crank having a cam roll thereon, a cam effective to intermittently actuate said cam roll and bell crank, and a second link directly connecting said two bell cranks, the second link being selectively connected to one of said bell cranks to vary the travel of said rod.

4. In a loom for weaving oriental rugs, a plurality of yarn dividers, a supporting shaft in which said dividers are mounted for angular movement about transverse parallel axes, a pinion on each yarn divider, a rack mounted in said shaft and operatively engaging all of said pinions, a cam actuated lever, and a link directly connecting said lever to said rack.

5. In a loom for weaving oriental rugs, a plurality of yarn dividers, a supporting shaft in which said dividers are mounted for angular movement about transverse parallel axes, a pinion on each yarn divider, a rack mounted in said shaft and operatively engaging all of said pinions, a cam-actuated lever, and a link directly connecting said lever to said rack, said link being adjustable relative to said lever to vary the longitudinal position of said rack.

6. In a loom for weaving oriental rugs, a plurality of yarn dividers, a supporting shaft in which said dividers are mounted for angular movement about transverse parallel axes, a pinion on each yarn divider, a rack mounted in said shaft and operatively engaging all of said pinions, means to intermittently reciprocate said rack, an arm and stud on said shaft, and a vertically movable cam-actuated link directly connected to said stud and effective to oscillate said shaft.

7. In a loom for weaving oriental rugs, a plurality of yarn dividers, a supporting shaft in which said dividers are mounted for angular movement about transverse parallel axes, a pinion on each yarn divider, a rack mounted in said shaft and operatively engaging all of said pinions, means to intermittently reciprocate said rack, an arm and stud on said shaft, and a vertically movable cam-actuated link directly connected to said stud and effective to oscillate said shaft, said

rack-reciprocating means including a swivel connection permitting oscillation of said rack with said shaft.

8. In a loom for weaving oriental rugs, a plurality of yarn dividers, a supporting shaft in which said dividers are mounted for angular movement about transverse parallel axes, a pinion on each yarn divider, a rack mounted in said shaft and operatively en-

gaging all of said pinions, a stud on said rack, a link connected thereto for reciprocating said rack, a slotted guideway for said stud fixed on the end of said shaft, and means to oscillate said shaft and guideway.

In testimony whereof I have hereunto affixed my signature.

MARIUS A. BAUER.
